CHARLES S. WALTON, OF LOS ANGELES, CALIFORNIA.

LOCK DEVICE FOR FUSE-BLOCKS OR CUT-OUTS.

1,164,148.

Specification of Letters Patent. Patented Dec. 14, 1915.

Application filed October 12, 1913. Serial No. 338,312.

To all whom it may concern:

Be it known that I, Charles S. Walton, a citizen of the United States, residing at Los Angeles, in the county of Los Angeles 5 and State of California, have invented a new and useful Lock Device for Fuse-Blocks or Cut-Outs, of which the following is a specification.

The primary object of this invention is to provide a means which will prevent unauthorized persons surreptitiously closing electric circuits, and in this way defrauding the power companies.

I find that the power companies, such as the Edison company, are annually defrauded and a considerable amount of their current used without being paid for, by persons who go into vacant houses where the fuses have been removed to break the electric circuits and without knowledge of the power company, inserting fuses into the fuse blocks or cut-outs, thus closing the circuits so that they may have power in the house. These new tenants very often leave a building before the company is aware that its current is being used therein, and in such cases no trace of them can be found in the majority of cases.

My invention aims to prevent this practice by providing a means for plugging the fuse sockets in such way that the plugs may only be removed by cutting or breaking a steel connection.

With these and other objects in view, the invention consists in certain novel features of construction, combination and arrangement of parts as will be hereinafter fully described, illustrated and claimed.

Referring to the drawings: Figure 1 is a top plan view of a fuse block showing my lock device applied thereto. Fig. 2 is a side elevation of Fig. 1. Fig. 3 is a longitudinal sectional view taken on the plane of line x^4-x^1 , x^5-x^6 , of Fig. 1. Figs. 4 and 5 are transverse sectional views taken on the plane of line x^4-x^1 , x^5-x^6 , respectively. Fig. 6 is a detail perspective view of a keeper forming a part of my invention. Fig. 7 is a detail perspective view of a yoke also forming part of my invention.

Referring in detail to the drawings by numbers, 1 designates as an entirety a fuse block of any commercial type and having in the present instance three sockets 2 arranged in alignment and adapted to receive the

fuses which close a circuit through the respective sockets as will be clearly understood by any one familiar with this part.

The terminals of the respective fuse sockets are designated by the numerals 3 and 4. Whenever the fuses are removed to break the circuit so that no power may be used, it is desirable to prevent unauthorized persons inserting such fuses within the sockets to again close the circuits, and I prevent this practice by the use of non-conducting plugs 5, 6, and the lock bar 7. The non-conducting plug 5 consists of a preferably porcelain body 8 to thread within one of the sockets 2 of the fuse block and this plug is provided with a longitudinal chamber 9 in its opening on its upper end, and in this chamber is rigidly secured by cement 10 or any other suitable means, a keeper or socket 11. Referring to Fig. 3, it will be seen that this socket 11 is of U-shaped construction having outwardly projecting flanges 12 formed on the terminals of the arms thereof, and the bight portion 13 being provided with an opening 14. The plug is also formed with a passage 15 extending from its lower end into communication with the chamber 9.

The plug 6 has a body similar to the plug 5 and provided with a recess 16 opening on its upper end and receiving a U-shaped bridge or yoke member 17 having outwardly projecting flanges 18 at the terminals of its side portions. The member 17 is anchored within the recess 16 by cement 19 or other suitable means, and it is of such length as to project a considerable distance above the top of the plug as best shown in Figs. 2 and 3.

The locking bar 7, which in conjunction with plugs 5 and 6, completes my invention, is provided at one end with a locking head 95 or snap consisting of a depending laterally projecting arm 7' having its end portion bent upwardly to form a spring tongue 20, which forms an acute angle with the arm 7'.

The method of using my lock device may be briefly described as follows: After the fuses have all been removed from the block the non-conducting plug 5 is screwed into one end socket 2, and the non-conducting plug 6 is screwed into the other end socket 2. Then the lock bar 7 is inserted through the yoke 17 and its head forced into the keeper 11 through the opening 14. When the tip of the tongue 20 clears the end wall of the opening, said tongue springs into 110

locking position, as shown in Fig. 3, and cannot be then removed without destroying the device. When the company owning the device desires to again make connections, the 5 spring head is cut on the dotted line 21 so that the bar may be slid through the yoke 17. The plug 5 may be then unscrewed, and the head drops through the passage 15 into the corresponding socket and may be easily 10 removed. This construction allows the non-conducting plugs to be used again without any repairs being necessary, although a new locking bar must be substituted. Referring to 15 2, it will be seen that it is impossible to remove the non-conducting plugs after they have been locked in place by the bar without destroying some part of the device. A non-conducting plug 22 may be placed in the central socket 2 if desired, although this is 20 not absolutely necessary.

From the foregoing description taken in connection with the accompanying drawings, it will be seen that I have provided a practical means for closing sockets or fuse 25 blocks to prevent fuses being placed therein, and while I have shown the preferred embodiment of my invention, it will be understood that the same idea may be carried out in other ways, and I wish to be protected 30 in the use thereof, and desire to be limited only by the scope and spirit of the appended claims.

What I claim is:

1. A lock device of the character described comprising a pair of threaded dummy plugs, one of said plugs being provided with an opening extending entirely therethrough, a keeper anchored within said opening and bridging the top thereof, the bridge portion 40 being provided with a slot, a yoke member rigidly secured to the other of said plugs, a locking bar slidable through said yoke member and provided with a spring tongue on one terminal to project through the slot into

the keeper and snap into locking engagement with the under side of the bridge piece. 45

2. The combination with a fuse block having a plurality of threaded fuse sockets therein, of non-conducting plugs screwed into the sockets, one of said plugs having 50 an opening therein, a plate closing said opening and having a central opening therein, a locking bar non-rotatably secured to the other of the plugs, a spring tongue on one terminal of said locking bar adapted to extend through the opening in said plate and snap into engagement with the plate at a point spaced from the opening therein. 55

3. A lock device for fuse blocks comprising a pair of non-conducting plugs adapted 60 to be threaded into a fuse block, a yoke member secured to one of the plugs, a locking bar slidable through the yoke member, a keeper plate having an opening therein secured to the other of the plugs, and a 65 spring catch carried by the bar and projecting through the opening in the keeper plate and locking with said keeper plate.

4. A lock device for fuse blocks comprising a pair of non-conducting plugs adapted 70 to be threaded into a fuse block, a yoke member secured to one of the plugs, a locking bar slidable through the yoke member, a keeper plate having an opening therein secured to the other of the plugs, a right-angled 75 generally extending arm carried on one end of the bar and projecting through the opening in the keeper plate, and a spring tongue carried by said arm and adapted to engage and lock with the under side of said plate. 80

In testimony whereof, I have hereunto set my hand at Los Angeles, California, this 3rd, day of October, 1914.

CHARLES S. WALTON.

In presence of—

RODNEY M. SMITH,
LORRAINE E. DURROW.
